[57] CLAIM

The ornamental design for a pull, as shown.

DESCRIPTION

FIG. 1 is a front elevational view of a pull which embodies the principles of my new design;

FIG. 2 is a bottom view of my pull;

FIG. 3 is an end view of the pull;

FIG. 4 is an enlarged fragmentary sectional view taken along the line 4—4 in FIG. 1; and

FIG. 5 is a sectional view taken along the line 5—5 in FIG. 2.
